UNITED STATES PATENT OFFICE

ETHEL MAE ZURBRIGG, OF TORONTO, ONTARIO, CANADA

ELECTRIC CHEMICAL VAPORIZER

Application filed November 9, 1925. Serial No. 67,863.

The invention relates to improvements in electric chemical vaporizers as described in the present specification and illustrated in the accompanying drawings that form a part of 5 the same.

One object of the invention is to provide a vaporizer which may be used as a unit in itself, or simply as a means of injecting chemical fumes, or vapor, into a cabinet bath. 10 A further object is to provide means whereby the vapor may be directed into two or more distributors for the treatment of a corresponding number of patients simultaneously.

A still further object is to provide for the 15 automatic breaking of the electrical circuit to the element upon the total evaporation of the water in the boiler.

And generally the objects of the invention 20 are to provide a chemical vaporizer which may be manufactured at a low cost and which 25 will be efficient in operation and safe.

The invention consists in certain novel features in construction, arrangements and combinations as will be more fully and particu- 30 larly pointed out hereinafter.

In the drawings Figure 1 is a diagrammatic view in perspective showing the vaporizer and a portion of the cabinet, parts of the device being broken away to disclose the in- 35 terior.

Figure 2 is a perspective view of the electric heating element.

Figure 3 is a perspective view of a modified 40 form of vaporizer, a portion of the supporting frame being broken away.

Like numerals of reference indicate corresponding parts in the various figures.

Referring to the drawings A represents a 45 boiler, which is preferably constructed in three sections, the lower, or base section, being adapted to contain the water, or other liquid, to be boiled and being constructed of material which is a non-conductor of electrical current, the intermediate section 2 being a hollow cyl- 50 inder supported on the flanged top edge 3 of the water receptacle 1, and also being constructed of insulating material, and the top section 4 being a substantially dome like closure 5 having a portion thereof offset at right angles and providing a horizontal outlet 6.

7 is an electric element consisting of two sets of metal plates 7^a and 7^b, of opposite polarity, supported free of engagement with one another from a bridge 8 mounted transversely within the intermediate section 2, said 55 element depending downwardly into the liquid receptacle and when properly electrified through the medium of the plug 9, suitably connected to the source of electric energy being adapted to boil said water to generate 60 steam.

10 is a compartment supported within the intermediate section 2 and having marginal communication with the steam generator positioned therebelow, said compartment being for the reception of the fume generating material 11, such as a mineral, or any desired chemical, which is to be vaporized through the action of the steam from the water in the receptacle 1. 70

While it is desirable that access may be readily had to the sections 1, 2 and 4 in order to replenish the supply of liquid, or fume generating material, still it is essential that said sections be securely locked together against 75 accidental displacement of said sections, and for this purpose a base 12 is provided on which the receptacle, or base section 1, is adapted to sit and a stirrup 13, pivoted thereto at each of its ends as at 14 and adapted to be 80 swung over the vaporizer and securely locked to the dome shaped top 5 by means of a screw 15 extending through said stirrup and adapted to be screwed into a threaded opening in an extension 16 from said top, is provided, thus 85 clamping the whole device securely to said base.

The base 12 is preferably provided with guide blocks, or locators, 16^a to insure the proper positioning of the vaporizer on the 90 base.

17 is a sub-base on which the base 12 is slidably mounted in the opposed guide flanges 18.

19 is one wall of a cabinet bath which is provided with a flanged inlet 20 located on 95 the same vertical plane as the vapor outlet 6 so that said outlet and inlet may be brought into register by simply sliding the vaporizer towards the cabinet the required distance.

21 is an electric receptacle carried on the 100

wall 19 in the same vertical plane as the plug 9 so as to effect the electrical connection simultaneously with the registering of the outlet 6 with the inlet 20, said receptacle being suitably connected in the electric circuit and being controlled by a switch 21^a, also positioned on said wall.

In the operation of the vaporizer hereinbefore described the receptacles 1 and 10 are first supplied with the required complement of liquid and fume generating material respectively and the sections assembled and locked together by means of the stirrup 13 and the vaporizer is moved to the proper position in relation to the cabinet wall 19 to bring the outlet 6 and the plug 9 into operative engagement with the inlet 20 and the receptacle 21 respectively, thus completing the electric circuit and causing the water or other liquid to be boiled, the steam therefrom causing the emission of fumes from the material in the receptacle 10. These fumes rise upwardly in the vaporizer and escape through the outlet 6 into the cabinet in which the patient is located.

In Figure 3 a modified form of construction is shown in which a vertical wall 22 is extended upwardly from the sub-base 17, towards and away from which the vaporizer is adapted to be operated between the guide flanges 18, said wall being provided with an opening 23 in alignment with the outlet 6 and on the side thereof opposite to that on which the vaporizer is mounted carrying a vapor distributing chest, or compartment, 24 having outlet flues 25, to any or all of which may be connected suitable connections leading to different cabinets. The outlets 25 not required may be closed by means of caps 26.

The electric connection in the modified device shown in Figure 3 is made by means of the plug 9 engaging a receptacle 27 carried by the wall 22, said receptacle carrying a cord 28 and plug 29 adapted to be connected up to any suitable source of supply.

The wall 22 is preferably provided at its top end with a hand grip 30 to facilitate moving the vaporizer from one place to another.

It will have been apparent from the foregoing that so long as the electric connection between the elements 9 and 21 are intact and there is conducting liquid in the receptacle 1 steam will be generated but immediately upon evaporation of said liquid the electric circuit through the element 7 will be broken, owing to the fact that said liquid being a conductor provides the resistance necessary to electrically connect the plates 7^a and 7^b, thus making it impossible to overheat the element.

While it is possible to collapse the stirrup 13 when the vaporizer is in operative engagement with the cabinet wall it is absolutely impossible to gain access to the interior of the vaporizer without withdrawing the va-

porizer from its connection with said cabinet, consequently breaking the electric circuit and thus eliminating all possibility of contact with the electric element while the circuit is closed.

What I claim is:—

1. In an electric chemical vaporizer, a water receptacle constructed of non-conductive material, a steam conducting element supported by said water receptacle and provided with a horizontally disposed outlet, an electric element carried by said steam conducting element and operating in said water receptacle to boil the water therein, an electric plug having connection with said element, means for suspending the chemical to be vaporized in said steam conducting element, a base, and a locking stirrup.

2. In an electric chemical vaporizer, a steam generator comprising a plurality of intercommunicating sections in superposed relation to one another, a base supporting said sections, a stirrup pivotally mounted on said base and adapted to be swung over said generator and detachably locked to the uppermost section thereof, a sub-base supporting said base, said generator being provided with a vapor outlet and an electric plug in vertical alignment, said base being slideable on said sub-base, an electric element positioned within said generator and connected to said plug, and means for suspending fume generating material between said element and said outlet.

Signed at the city of Toronto, Ont., this 17th day of October, 1925.
